FOREIGN PATENT DOCUMENTS

CN 307737328 * 6/2022

Primary Examiner — Brett Miller
Assistant Examiner — Sara Michie Pottenger(57) **CLAIM**

The ornamental design for a safety gate, as shown and described.

DESCRIPTION

FIG. 1 is a top, front, left side perspective view of a safety gate showing our new design;

FIG. 2 is a bottom, rear, right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a bottom plan view thereof; and,

FIG. 8 is a top plan view thereof.

The broken lines show features of the safety gate that form no part of the claimed design.

1 Claim, 8 Drawing Sheets---
